UNITED STATES PATENT OFFICE.

DAVID HEYMAN, OF NEWARK, NEW JERSEY.

MECHANICAL AUTOMOBILE TOY.

Application filed November 14, 1925. Serial No. 68,972.

This invention relates to improvements in mechanical automobile toys. The chief object of this invention is to provide an inexpensive but effective toy that will simulate a 5 swaying or rocking automobile, or one that is out of control of the operator.

The manner in which I carry out my invention will now be described, and the novel features thereof will be pointed out in the 10 appended specification and claims.

In the accompanying drawings, Figure 1 is a side view in elevation of my invention,

Figure 2 is a fragmental side elevation of certain parts of my invention, shown in operating position,

Figure 3 is a sectional view taken on line 3-3 of Fig. 1 showing the operating mechanism.

The toy of my invention consists of a body 20 portion 5. Hingedly connected to said body portion 5, as at 6, is a cradle or frame 7. At the forward end of the cradle 7 there is pivotally mounted at 8, the forward end or hood portion 9 of my toy automobile, this 25 forward portion has mounted at the front end thereof the front axle and wheel 10, and the rear wheels 11, and axle 12 is mounted at the rear of the cradle 7.

The front or hood portion 9 has at one 30 side thereof a slotted arm 14, the object of which will presently be described.

The motive power of my automobile toy is supplied by the usual spiral spring 15, one 35 end of which is secured to a wall 16, of the cradle 7, and the other end being secured to a winding key shaft 17 of square cross section, loosely mounted on said shaft 17 is a gear 18, to one side of said gear 18 is a slidably mounted pawl 19 on said shaft 17; said 40 pawl 19 being held against ratchet teeth 20 punched out of the gear 18, by means of a spring 21 held on the shaft 17 pressing against one face of said pawl 19 and the inner surface of wall 22 of the cradle 7, said 45 pawl 19 being operative in driving direction only. Forward motion of my toy automobile is imparted by means of gear 18, which is in mesh with a pinion 24 secured to the rear axle 12. Up and down rocking motion 50 to the toy is imparted by means of a pinion 25, secured to a crank shaft 26 having at one end a crank or offset portion 27 fitting into a slot 28 in the arm 14 of the front or hood portion 9, the crank shaft 26 has at its opposite end another offset 29, operating in a 55 slot 30 in the lower part of the body portion.

From the foregoing it will readily be seen that when forward motion is imparted to my toy through the medium of the power spring 15 and driving gear 18, an up and down 60 movement is imparted to the body 5 of the car by means of crank 29, operating in slot 30 in the said body portion 5, and also an up and down rocking or swaying motion will be imparted to the forward or hood portion 65 of the toy by means of crank 27 operating in the slot 28 to raise and lower arm 14 about its pivot 8 and thus cause an up and down oscillating movement to the hood portion of my toy. A sidewise or swaying motion is 70 effected due to the body of the car being pivoted at 6-6 and is therefore free to sway sidewise when the body of the car is being swayed up and down by the crank 29. Inside of the car and mounted upon a spring 75 32, fixed to a seat 33, is a figure of a chauffeur 34. It will be readily seen that when the toy is in motion the said figure of a chauffeur will sway from side to side and will simulate fear and lack of control of the 80 machine.

It will also be readily seen by referring to Figs. 2 and 3 of the drawings that the main driving gear 18 is loosely mounted on the shaft 17 and said gear is only actuated for 85 advancing rotary movement, on the unwinding of the spring 15, by means of the pawl 19, acting against ratchet teeth 20 of said gear 18. This arrangement permits of the use of a single gear and the pinion 24 mounted on axle 12 to produce movement of the toy in proper forward direction.

Having described my invention, what I claim is:

1. In a toy of the nature described, a forwardly disposed hood portion, a body portion pivotally associated with the hood portion, an arm on said hood portion having a slot therein and means operating within the slot of said arm to oscillate the hood 100 in an up and down direction.

2. In a toy of the nature described, a hood portion, a body pivotally associated with the hood portion, said body having a slot therein, toy propelling mechanism associated with the body, and an arm on the propelling mechanism operating in said slot to oscillate the body in an up and down direction.

3. In a toy, a hood portion, a body portion having a slot therein, a cradle pivotally 110 associated with both the hood and body portions, a slotted arm on the hood portion,

- and means associated with the slotted arm of the hood and the slot in the body to simultaneously oscillate the hood in a vertical direction and the body in a vertical 5 and lateral direction.
4. In a toy, a body member, a pivotally connected frame associated with said body member, a forwardly disposed hood portion pivotally connected to said frame, a slotted arm fixed to said hood portion, and means associated with the said arm to rock the hood portion about its pivot.
5. In a toy, a body member, a pivotally connected frame associated with said body portion, a forwardly disposed hood portion pivotally connected to said frame, a slotted arm fixed to said hood portion, a crank shaft mounted in said frame one end of said crank shaft passing through said slotted arm, and 10 means for actuating said crank shaft.
6. In a toy, a body member, a pivotally connected frame associated with said body portion, a forwardly disposed hood portion pivotally connected to said frame, a slotted 15 arm fixed to said hood portion, a winding key having an extended shaft thereon, a driving mechanism suitably mounted on said key shaft, a crank shaft mounted in said frame, one end of said crank shaft passing through said slotted arm, and a 20 pinion mounted on said crank shaft and adapted to be actuated by said driving mechanism to impart an oscillatory movement 25 to said hood portion.
7. In a toy, a forwardly disposed hood, a body, a cradle pivotally connected to the hood and body, a motor mechanism in the cradle and a crank shaft actuated by the motor mechanism and associated with the hood and body for producing a different rocking 30 movement of the body and hood relatively to each other.
8. In a toy, a forwardly disposed hood portion, a body portion loosely associated 35 with said hood portion, a frame pivotally associated with said body portion, a winding key shaft rotatively mounted in said frame, a driving mechanism suitably mounted on said key shaft, a rear axle loosely mounted 40 in said frame having wheels rotatively mounted thereon, a pinion fixed to said axle, for rotating said axle and wheels, a crank 45 shaft rotatively mounted in said frame, and an offset portion at one end of said shaft 50 adapted to cooperate with a slot in the said body portion to cause the said body portion to have a vertical rocking movement.
9. A toy comprising a motor, a body member, a depending frame pivotally connected to said body member, a rotatable axle and 55 wheels carried by said depending frame, a hood portion pivoted to said depending frame, a rotatable axle and wheels carried by said hood section and means on said motor for rocking said hood and body sections. 60
10. A toy comprising driving means, a body member, a depending frame pivotally connected to said body member, a rotatable axle and wheels carried by said depending frame, a hood portion pivoted to said depending frame, a rotatable axle and wheels carried by said hood section, a crank shaft 65 associated with the hood portion and rotatively mounted in said frame, a pinion fixed to said crank shaft said pinion being adapted to mesh with the aforementioned driving means, and means on said crank shaft to cause relatively different rocking movement 70 between said body portion and said hood portion.
11. In a toy, a body member, a cradle beneath the body member pivotally suspended therefrom at the front and rear thereof, a hood at one end of the body pivotally connected to the cradle, toy propelling mechanism mounted in the cradle, a slotted arm on the hood and means on the propelling mechanism coacting with the slotted arm for vertically oscillating the hood. 75
12. In a toy, a body member having a slot 80 therein, a pivotally connected cradle associated with said body portion, toy propelling mechanism mounted in the cradle and an arm on the propelling mechanism coacting with the slot in the body to oscillate the body 85 in a vertical direction.
13. In a toy of the nature described, a hood portion, a body pivotally associated with the hood portion, said body having a slot 90 therein, toy propelling mechanism associated with the body, and a crank shaft on the propelling mechanism operating in said slot to actuate the body to oscillate it in an up and down direction. 95
- In testimony whereof I hereunto affix my 105 signature.

DAVID HEYMAN.
